UNITED STATES PATENT OFFICE

JOHN HUDSON HOWE, OF SOUTH ORANGE, NEW JERSEY

LOOP FORMING AND CUTTING DEVICE

Application filed December 31, 1931. Serial No. 584,260.

This invention relates to devices for the forming and the cutting of loops in relation with fabric. The device of the invention is capable of many uses, one of which is the making of hooked rugs.

The principal object of the invention is to provide a device of simple construction and having features which adapt it to perform its intended function very efficiently.

10 The device is also so constructed that it is easily operable by any one.

The device of the invention comprises essentially a pair of relatively movable supporting members, one of which carries a stationary needle and the other of which carries an oscillatory loop former. The device also includes suitable means for oscillating the loop former in proper relation to the needle during relative movement of the supporting members. The loop holder when actuated by said means is adapted to pick up a stitch taken by the needle and form a loop while the needle takes the next stitch. A further feature of the device resides in the provision of a cutting device which is resiliently supported in cooperative relation to the loop former and is adjustable into operative or inoperative position depending upon whether or not the particular operator desires to cut the loops formed by the loop former.

Other objects and features of construction of the device will be apparent hereinafter. The following detailed description will afford a complete understanding of a preferred embodiment of the invention as illustrated on the accompanying drawings.

Fig. 1 is a side elevational view of the device with the cutting device in inoperative position and illustrating clearly the manner of forming successive loops;

Fig. 2 is a view of the device of Fig. 1, looking at the same from the right side thereof;

Fig. 3 is a sectional view through the center of the device or along line 3-3 of Fig. 4, the cutting element being illustrated in operative position;

50 Fig. 4 is a view of the device as illustrated

in Fig. 3, looking at the same from the right thereof; Fig. 5 is a sectional view along line 5-5 of Fig. 1;

55 Fig. 6 is a detail view of the cutting device assembly;

Fig. 7 is a view of the assembly illustrated in Fig. 6 from the right side thereof;

60 Fig. 8 is a plan view of the assembly of Fig. 6; and

Fig. 9 is a detail view of the cutting device removed from its assembly.

Referring particularly to Figs. 1 to 4 of the drawings, and especially to Fig. 3 where the device is shown in section, the device as illustrated comprises essentially a supporting member designated generally by reference character 1, a stationary needle 2 carried thereby, a second supporting member 3 cooperatively associated with supporting member 1 so as to be movable relatively thereto, and an oscillatory or pivoted loop former 4 carried by supporting member 3. Supporting member 1 preferably comprises a wooden handle 5 and a pair of metallic plates or 70 walls 6 and 7 attached in spaced relation to the handle in any suitable manner, such for example, as by means of screws as illustrated. As illustrated in Fig. 3, needle 2 rests against the upper part of handle 5 and is disposed 75 between and attached to the parallel side walls 6 and 7. The needle is provided with an eye opening 8 near its pointed end through which the yarn is passed. The needle is so formed that eye 8 comprises a substantially 80 longitudinal opening through which the yarn may readily pass, as shown more clearly in Fig. 3. The needle is also formed with parallel extending edges 9 on both sides so that it constitutes a pair of channels through which 85 the loop former and yarn pass in operation, as will be more clearly apparent hereinafter.

90 The loop former is also provided with extending parallel edges 10 to form a channel through which the cutting device, to be described hereinafter, passes when in operation. The upper end of the loop former is recessed and provided with a pair of retainer lugs 11 (see Fig. 4) to receive the yarn and hold it 95 firmly so as to form the desired loop.

Supporting member 3 comprises a supporting block 12 having a laterally extending handle 13 and parallel guide arms 18 and 19 (see Fig. 5) securely attached thereto. Supporting block 12 is positioned in the space between walls 6 and 7, as shown in Fig. 5, and is adapted for slidable movement between these walls. The walls are recessed at 16 and 17 respectively, and the parallel guide arms 18 and 19 are disposed within the recesses and adapted for slidable movement therein. Thus, the recesses and the arms serve as a retaining and guiding means for supporting member 3 during its reciprocating movement. The channel walls of the loop former are widened as at 14 (see Figs. 3 and 4) to provide a presser foot portion 20 whose purpose will be clearly apparent hereinafter. The widened channel walls thus serve a dual purpose.

Supporting block 12 threadedly carries a laterally extending bolt 21, which in turn carries an ear 22 upon which the loop former is mounted for pivotal action, the widened channel walls of the loop former being pivotally attached to the ear. Spaced cam followers 23 and 24 are securely attached to the loop former, as illustrated in Fig. 3, and are adapted for engagement by the cam-like ends of a leaf spring 25 which is securely attached to handle 5. The ends of this spring are bent as illustrated to protrude into the space between walls 6 and 7 so as to constitute the desired cam surfaces for actuating the loop former in a manner to be set forth in detail hereinafter. Suitable screws 26 and 27 may extend through handle 5 so as to engage the upper and lower ends of spring 25 and serve as supporting means therefor. A small cam 49 (see Figs. 3 and 5) is rotatably carried between walls 6 and 7 and is actuatable by operating arm 50 (see Fig. 1) attached to its shaft. The arm and wall 6 have co-acting knobs and depressions to retain the cam in adjusted position. The purpose of the cam is to vary the size of a stitch as will appear hereinafter.

Supporting member 1 also functions through the medium of walls 6 and 7 to adjustably support the cutting device assembly, designated generally by reference character 28 and illustrated in detail in Figs. 6 to 8. As shown in Fig. 3, walls 6 and 7 are slotted at their upper ends as at 29, the purpose of the slots being to slidably receive and support the cutting device assembly. This assembly comprises a supporting block 30 having opposed guide portions 31 which are normally disposed within slots 29 of walls 6 and 7 and adapted to slide therein. The supporting block is also formed to provide an extending threaded stud portion 32 for receiving a knurled nut 33, the purpose of which will be clearly understood later. An adjustable screw 51 is centrally carried by block 30 and

serves as a stop to vary the size of the stitch taken, as will appear later. An extending ear 34 of the supporting block pivotally carries a link 35 which is bifurcated at its upper end to embrace ear 34. At the lower end 70 of link 35, the cutting device support 36 is pivotally mounted.

The cutting device 37, which constitutes an important feature of the invention, is adapted for removable mounting upon support 36. A loop holder 38 comprising support assembly 39 and pointed needles 52 is resiliently carried by support 36. Assembly 39 comprises an L-shaped arm 53 and a spring 54. These elements are attached to support 36 at 55. A pin 56 carried by spring 54 extends through apertures in arm 53, device 37, and support 36 to normally lock the cutting device in place.

The cutting device comprises a pair of scissor-like blades 40, having opposed sharpedges 41, and a supporting sleeve 42 which surrounds and firmly embraces the blades. Hole 43 provided in the lower portion of the cutting device is adapted to receive pin 56 when the cutting device is mounted in cooperative relation upon support 36. It will be apparent that by flexing spring 54 the cutting device may be readily mounted or removed for any purpose. A spring 44, which preferably takes the form illustrated in Fig. 6, has one end attached to supporting block 30, as at 45, and its other end slidably engages support 36, as at 46.

Referring now to Fig. 3, it will be apparent that with the cutting device assembly just described mounted properly for slidable action upon walls 6 and 7 of supporting member 1, such assembly may be positioned in its uppermost or operative position, as illustrated in Fig. 3, and may be retained there by tightening nut 33 or it may be moved to its lowermost or inoperative position, as illustrated in Fig. 1, by merely loosening nut 33, sliding the assembly downward, and again tightening nut 33. It will be apparent that the inner face of the adjusting nut 33 bears against the outer edges of walls 6 and 7 to maintain the assembly in adjusted position.

It will also be noted that by virtue of the arrangement of elements constituting the cutting device assembly, as illustrated clearly in Figs. 3 and 6 and as described above, cutting device 37 and loop holder 38 are free to move transversely with respect to their supporting block 30 and the cutting device is urged continually into engagement with loop former 4 by spring 44.

Considering now the operation of the device as a whole, and assuming that it is desired to merely form loops, then the cutting device assembly may be moved into inoperative position, as shown in Figs. 1 and 2. In Fig. 1, the device is illustrated in cooperative relation with fabric 47 and the loops are 130

shown at 48. Several formed loops are shown and the needle is shown just after having taken a stitch. By virtue of the peculiar design of the needle, as explained above, the 5 yarn lies in the channel formed on one side of the needle. In operation, the device is positioned adjacent one side of the fabric, as illustrated, and the needle is pushed through the fabric, carrying with it the material with 10 which it is threaded. The device is now in the condition illustrated in Fig. 1. Cam follower 23 has been actuated to force the loop former against the needle. The supporting member 3 is now moved toward the fabric 15 by means of handle 13. The loop former 4 is thus moved forward by its supporting member and rides along the channel of the needle, to the eye thereof to pick up the material and form the loop. The needle is now 20 withdrawn and cam follower 24 is engaged by the upper end of spring 25, as illustrated in Fig. 3, to oscillate the loop former relative to the needle. Since the loop former is held stationary, the needle is moved away from 25 the loop former at the moment that the needle withdraws from the fabric. Presser foot portion 20 of the loop former limits the movement of the loop former through the fabric. The special formation of the needle eye to 30 provide a longitudinal opening allows the yarn to lie flat in the needle channel.

By virtue of the oscillatory action of the loop former relative to the needle, the needle is now spaced therefrom and is ready to take 35 the next stitch through the fabric at a proper spacing from the stitch just completed. When supporting member 1 is again moved forward, the needle takes the next stitch, and subsequent backward movement of supporting member 3 withdraws the loop former 40 from the fabric. As its cam follower 23 engages the lower end of spring 25, the loop former is again moved into engagement with the needle so as to be ready to pick up the 45 next stitch in the same manner as just described. Since the cutting device is in inoperative position, it is ineffective to cut the loops and merely rests against the lower portion of the loop former. Because of its in- 50 operative position, this device does not enter the fabric. It is important to note however at this time that either screw 51 or cam 49 or both may be used to limit the oscillatory movement of the loop former and thus limit 55 the size of the stitch taken. The end of screw 51 serves as a stop against which link 35 abuts and since the cutting device assembly oscillates with the loop former, the size of the stitch may be varied by moving screw 60 51 in or out. Likewise cam 49 may be rotated to adjustably limit the oscillatory movement of the loop former.

Assume now that it is desired to cut the loops that are formed by the device after 65 the forming thereof in the manner just de-

scribed. In such case, the cutting device assembly is moved into operative position as illustrated in Fig. 3. This results, of course, in the moving forward of the cutting device and the loop holder. The device is now 70 operated in the manner described above to form successive loops, the needle and loop former operating in the manner described. Since the cutting device is carried upon walls 6 and 7, this device is moved with supporting member 1 in the same manner as is needle 2. The cutting device, rests against the loop former and rides in the channel thereof except when the cutting device is in the fabric 75 and the loop former is withdrawn. When the loop former is in its extended position, as shown in Fig. 3, to form a loop, movement of the supporting member 1 to insert the needle through the fabric to take the next 80 stitch causes forward movement also of the cutting device which rides along the loop former and shears or severs the loop at its central point. At the same time, the pointed needles 52 of the loop holder which lie between the widened channel walls of the loop 85 former engage the material and fabric as at 57 (see Fig. 3) to prevent slipping of the loop by pulling of the cutting device. Obviously, the loop holder thus keeps the pile 90 even. Subsequent withdrawal of the needle from the fabric results also in the withdrawal of the cutting device therefrom. This cooperative relation of the elements of 95 the device causes successive formation of loops and the cutting thereof, as illustrated in Fig. 3. The severed loops constitute the pile which it is desired to form on the fabric.

It will be apparent from the present disclosure that a device embodying the various features set forth in detail is highly efficient 100 in performing its intended function. Since the parts are relatively simple, there is little likelihood that the device will get out of order, and the only appreciable wear is upon the cutting device which tends to become 105 dull after long periods of use. By virtue of the novel construction of the cutting device assembly, however, the cutting device may be readily removed, as described above, without in any way dismantling the device. The parts are so designed that ready access 110 is had to the cutting device for removal. Other desirable features will be apparent to those skilled in the art.

It will be understood that various changes and modifications in the various details of the device are possible and are contemplated by the invention. The purpose of the present disclosure is for illustration only and any such modifications as come within the scope 115 of the appended claims are deemed to be within the scope of the invention.

I claim:

1. A device of the class described, comprising 120 a pair of relatively slidably supporting

members, a stationary needle carried by one of said members, a loop former pivotally carried by the other of said members, a cam follower on said loop former on each side of the pivot point thereof, and spaced cams on said one member adapted to engage said cam followers to actuate said loop former in relation to said needle as said members are relatively moved.

10. 2. A device of the class described, comprising a pair of relatively slidable supporting members, a stationary needle carried by one of said members, a loop former pivotally carried by the other of said members, a cam follower on said loop former on each side of the pivot point thereof, and a leaf spring on said one member having cam-like ends adapted to engage said cam followers to pivotally actuate said loop former in relation to said needle as said members are relatively moved.

15. 3. A device of the class described for forming and cutting loops, comprising a pair of relatively movable supporting members, a stationary needle carried by one of said members, an oscillatory loop former carried by the other of said members, means for oscillating said loop former in relation to said needle as said members are relatively moved, and means for severing the formed loops.

20. 4. A device of the class described for forming and cutting loops, comprising a pair of relatively movable supporting members, a stationary needle carried by one of said members, an oscillatory loop former carried by the other of said members, means for oscillating said loop former in relation to said needle as said members are relatively moved, means for severing the formed loops, and means for holding the loops simultaneously with the severing thereof.

25. 5. A device as claimed in claim 3, said severing means comprising a cutting device resiliently supported in cooperative relation to said loop former, and means urging said device into contacting engagement with said loop former.

30. 6. A device of the class described for forming and cutting loops, comprising a pair of relatively slidable supporting members, a stationary needle carried by one of said members, an oscillatory loop former carried by the other of said members, means for oscillating said loop former in relation to said needle as said members are relatively moved, whereby said loop former picks a stitch off the needle to form a loop, and a cutting device adjustably carried by said one member and adapted to cut the formed loop when desired.

35. 7. A device of the class described for forming and cutting loops, comprising a pair of relatively slidable supporting members, a stationary needle carried by one of said members, an oscillatory loop former carried by the other of said members, means for oscillating said loop former in relation to said needle as

said members are relatively moved, whereby said loop former picks a stitch off the needle to form a loop, a cutting device adjustably carried by said one member and adapted to cut the formed loop when desired, and a loop holder also adjustably carried by said one member and adapted to hold the loop simultaneously with the severing thereof.

8. A device of the class described for forming and cutting loops, comprising a pair of relatively slidable supporting members, a stationary needle carried by one of said members, an oscillatory loop former carried by the other of said members, means for oscillating said loop former in relation to said needle as said members are relatively moved, whereby said loop former picks a stitch off the needle to form a loop, a cutting device adjustably carried by said one member, and means urging said cutting device into engagement with said loop former to effect shearing of the formed loop by said device.

9. A device of the class described for forming and cutting loops, comprising a pair of relatively slidable supporting members, a stationary needle carried by one of said members, an oscillatory loop former carried by the other of said members, means for oscillating said loop former in relation to said needle as said members are relatively moved, whereby said loop former picks a stitch off the needle to form a loop, a cutting device adjustably carried by said one member, means urging said cutting device into engagement with said loop former to effect shearing of the formed loop by said device, and means for holding the loop simultaneously with the severing thereof.

10. In a device of the class described, a removable cutting device comprising a pair of scissor-like blades having oblique cutting edges, and means rigidly attaching said blades together with their cutting edges in opposed relation.
